UNITED STATES PATENT OFFICE.

ALEXANDER JUDE, OF BIRMINGHAM, ENGLAND, ASSIGNOR TO BELLISS & MORCOM LIMITED,
OF BIRMINGHAM, ENGLAND.

TURBINE.

No. 895,644.

Specification of Letters Patent.

Patented Aug. 11, 1908.

Application filed October 3, 1906. Serial No. 337,254.

To all whom it may concern:

Be it known that I, ALEXANDER JUDE, subject of the King of Great Britain, residing at Ledsam Street Works, Birmingham, in 5 the county of Warwick, England, have invented new and useful Improvements in Turbines for Expansible Fluids, of which the following is a specification.

This invention relates to turbines for expansible fluids, the principal feature of which is the employment of improved constructions and arrangements for obtaining a balance of the fluid-pressure forces on the rotor in the direction of its axis of revolution, the rotor 15 being entirely or partially of drum formation.

The system of balancing to which the improvements, which form the subject of this application for a patent, are applied may be 20 described as that in which the flow of the stream of operating fluid along the length of the rotor is, in the initial portion of its path, in one direction and in the terminal portion in the opposite direction.

25 For convenience in reference it will be advantageous to give this system a name, the name adopted being "the to and fro balance system", this system being distinguished from that other system of balancing in 30 which, by the duplication of the operating organs, one half the stream flows in one direction and the other half in the opposite direction. In such a "to and fro" system the fluid may be admitted to the rotor at some 35 intermediate portion of its length and, after flowing in one direction to the end of the rotor, the fluid will be required to be conveyed along a passage, this being an inactive portion of its path, and admitted to other 40 operative organs of the rotor to traverse them in the opposite direction to the second end of the rotor. Alternatively to this, the fluid may have an inverted direction of flow, being admitted at one end of the rotor and 45 caused to finally escape from the rotor at an intermediate portion of its length. Certain important advantages over the former accompany such an inversion of flow as will be presently explained. One of my improvements 50 consists in conveying the fluid, in the inactive portion of its path, through the interior of the rotor instead of along a passage formed in or added to the stator:—Also to obtain, conveniently, a balance of the forces, 55 by the "to and fro" system above described,

when a large range of expansion is employed, I find it very advantageous, in the initial stage of the fluid action, to employ a disk-wheel of relatively large diameter, in the subsequent stages a drum or drums being employed for the body of the rotor. By means of such a disk-drum combination the diameters of the successive portions of the rotor, which are requisite to bring about a balance of the fluid pressures, will also permit of appropriate peripheral speeds, also, by the same means, the tendency for the fluid to leak past the shaft at the two ends of the stator casing or from one section of the casing to the other will be minimized.

70 The invention includes also a special method of mounting the rotor on the shaft and securing it thereto, to minimize the stresses and strains which may arise from differences of temperature and to facilitate 75 the assembly of the parts of the rotor.

Besides the advantage of avoiding the employment of balance pistons or, the alternative, namely avoiding the duplication of the operative organs of the turbine, the "to and fro" system of balancing, adopted in this invention, lends itself to the obtainment of important advantages in respect to the reduction of the leakage of air into, and steam or other fluid from, the stator casing at the ends 85 through which the shaft emerges.

Supposing steam to be the fluid employed, then, by the adoption of suitable proportions, it will, particularly when the disk-drum combination is employed, be easy to arrange for 90 the pressure at one end of the casing to be slightly in excess of the atmosphere, thus avoiding the possibility of the entrance of air and minimizing the liability to the outward leakage of steam. By a known contrivance, 95 the advantage of a like pressure at the other end of the casing can be secured when the above mentioned inverted direction of flow is adopted.

To facilitate description and shorten the 100 references, the above mentioned flow arrangement will be named "in at end-out at middle" type and the alternative will correspondingly be named "in at middle-out at end" type.

To minimize the loss by leakage from one 105 section of the casing to another, I employ my device for utilizing leakage steam as described in the specification of my patent application #330585, Series 1900.

Referring to the accompanying drawings:— 110

Figure 1 is a longitudinal section of a turbine of the "in at end-out at middle" type with inactive flow within the rotor and with the disk-drum combination, and containing also 5 the device for making the pressure at both ends of the stator casing equal to one another, the pressure at those ends being arranged to approximate to that of the atmosphere. Figs. 2 and 3 show details of Fig. 1. Fig. 4 10 is a part longitudinal section of a turbine, which also is of the "in at end-out at middle" type but without the disk-drum combination. Fig. 5 is a longitudinal section of the same 15 type in respect to the direction of flow, in which the disk-drum combination is employed but in which the inactive flow takes place through a pipe secured to the stator instead of passing through the rotor. Fig. 6 is a longitudinal section of a turbine of the 20 "in at middle-out at end" type with inactive flow within the rotor and with the disk-drum combination. Figs. 7 and 8 show details of Fig. 6 and are alternative to those of Figs. 2 and 3. Fig. 9 is a part longitudinal section 25 of a turbine, also of the "in at middle-out at end" type but without the disk-drum combination, and—Fig. 10 is a longitudinal section of another turbine of the "in at middle-out at end" type in which the disk-drum 30 combination is employed but in which the inactive flow takes place through a pipe secured to the stator.

Referring to Fig. 1 the fluid is admitted through the branch *a* to nozzles which direct 35 it to impinge on vanes secured to a disk-wheel *b*. Two sets of vanes on the wheel *b* are shown, with intermediate guide blades secured to the stator, whereby the very considerable kinetic energy of the fluid derived 40 by a drop of pressure of, or about, one-half the initial pressure can be efficiently utilized. In this first stage of the action, the construction and arrangements are such that the pressure in the spaces *c* and *d* on the two 45 sides of the disk-wheel *b* is the same. From *d* the fluid flows past a series of vanes secured to the drum portion *e* of the rotor, which vanes are alternated with the guide blades or nozzles with partial admission which are secured to the stator.

At *f* there will be a reduced pressure and the expanded fluid will be caused to flow past another alternated series of nozzles and vanes, the latter being secured to a drum 55 portion *g* of the rotor. On arriving at *h* the fluid will have fallen to a still lower pressure and will then be conducted through the interior of the drum-portion *i* of the rotor past helically shaped webs formed in rings *j* and *k* 60 (Figs. 2 and 3), which support the portion *i* of the rotor-drum. The flow through *i* will be inactive as far as the production of mechanical energy is concerned.

On emerging from *i* into the space *m* the 65 fluid will be directed to turn along the out-

side of the drum *i* past a further alternated series of nozzles and vanes, at the end of which it will enter the space *n* divested as fully as possible of pressure and velocity head.

In the spaces *h* and *n* there will be a difference of pressure which will tend to cause a leakage of fluid past the separating diaphragm *o*. To minimize the loss thereby and at the same time avoid frictional contact of rotor and stator I may adopt my 70 guide-blade and vane system of utilizing leakage fluid as described in the specification of my patent application #330585, Series 1900, or I may use any other known 75 method of lessening the leakage of fluid past a working joint.

If steam is the operating fluid and a condenser is employed, then, by the adoption of suitable proportions it will be possible with 80 this direction of flow along drum rotors on the "to and fro" system to obtain an approximate longitudinal balance of the fluid forces on the rotor and at the same time to maintain in the space *m* a pressure nearly 85 equal to that of the atmosphere, preferably a little in excess, to avoid the inflow of air past the shaft and the impairment of the 90 vacuum in the condenser.

In the space *c* at the other end of the stator 95 casing the fluid pressure will still be considerable, though very much less than the initial pressure. To eliminate leakage of fluid past the shaft at this end of the casing the following already known device may be 100 employed.

Beyond the space *c* a small chamber *p* is provided into which the fluid may leak from *c*, the loss being minimized by the employment here also of the before mentioned contrivance of patent application #330585, Series 1900, or other method of lessening leakage. To connect the chamber *p* and the space *m* a pipe *q* is provided through which the leakage fluid will be passed to join that 105 which emerges from *i* and be conducted past the nozzles and guide blades outside the drum *i* thus assisting in driving the turbine.

The fluid pressure in *m* being approximately atmospheric, as before described, the 110 trouble of leakage of fluid past the shaft may thus be avoided at both ends of the casing.

In the construction shown in Fig. 4 the disk-wheel *b* and the initial stage of the fluid action are omitted.

According to Fig. 5 the construction and operations up to the space *h* are the same as in Fig. 1 and so also after the fluid has reached the space *m*, the distinctive difference between Figs. 1 and 5 consisting in the 115 means for providing the inactive passage of the fluid from *h* to *m*, a pipe *r* being provided for this purpose in the construction shown in Fig. 5.

Figs. 6, 9 and 10 show examples of the 120

"in at middle-out at end" type of balanced turbine. In Fig. 6 the fluid is admitted at a^1 to a wheel b^1 , and flows from d^1 , in a direction from right to left, along the vanes of the drums e^1 and g^1 to the space h^1 from which it passes inactively through the interior of the drums e^1 g^1 to the space m^1 . From m^1 the fluid flows in a direction from left to right along the vanes on the drum i^1 and emerges 10 at the end of the rotor into the space n^1 from which it is finally evacuated.

In its inactive passage within the rotor it flows through holes which are bored obliquely through the web plates of the rings 15 j^1 and k^1 (Figs. 7 and 8) which support the ends of the compound drum $e g$. As in Fig. 1 the pressure in the spaces c^1 and d^1 on the two sides of the wheel b^1 are alike. In the space c^1 the pressure will be greatly in excess of that in m^1 on the other side of the separating diaphragm o^1 , the difference in the two pressures being much greater than on the two sides of the corresponding diaphragm o of Fig. 1. Means for minimizing 25 the loss by leakage are employed as in Fig. 1 but the loss thereby will necessarily be greater than in the "in at end-out at middle" type. Also, supposing steam to be the operating fluid and a condenser employed, 30 there will be a vacuum in the space n^1 which will tend to cause a leakage of air past the shaft and so impair the vacuum. Accordingly in this respect also, the "in at end-out at middle" type has an advantage.

35 Fig. 9 shows, in part view, a corresponding construction but with the disk-wheel omitted.

Lastly Fig. 10 shows how the fluid is conveyed from the space h^1 to the space m^1 along a pipe r^1 outside the rotor. Also in 40 this figure the separating diaphragm o^1 is shown embracing a somewhat large boss s of one of the end plates of the drum i^1 . The boss s constitutes virtually a balance piston and the construction shows how the two 45 systems of balancing may be combined. In this case the piston device is employed to compensate for a minor difference of the forces on the rotor instead of being required to balance the entire or major force of the 50 fluid pressure as ordinarily employed up to the present. Also, in Fig. 10 is shown a special method of mounting the rotor on its shaft. According to this, the wheel b^1 and the boss-plate s are both made to tightly fit 55 a tapered portion t of the shaft, between the plate s and a second boss-plate u , at the other end of the drum i^1 , a sleeve v is interposed. The portion w of the shaft is screw threaded

and, by means of a nut x , the boss of the wheel b^1 and the plate s are forced tightly on 60 to the tapered portion t of the shaft, no key being employed at this portion though one is fitted to secure the boss-plate u to the shaft and another at the other end of the rotor. The plate u is made thin enough to 65 be sufficiently flexible to yield and compensate for differences of temperature in drum and shaft.

I claim:

1. A turbine comprising a stator, a hollow 70 compound rotor consisting of a disk wheel and drums, means for introducing the operating fluid to the operative surface of the rotor, means for causing the whole of the fluid to flow in one direction along a portion 75 of the length of the operative surface of the rotor, means for causing the whole of such fluid to flow in the reverse direction along another portion of the length of the operative surface of the rotor, and to reach that 80 portion along the hollow body of the rotor, and means for conveying such fluid away from the turbine.

2. A turbine comprising a stator, a compound rotor consisting of a disk wheel and 85 drums, means for introducing the operating fluid to the operative surface of the rotor at one end thereof, means for conveying the whole of such fluid away from such operative surface at an intermediate portion of the 90 length of the rotor and means for reintroducing it to the operative surface at the other end thereof, and means for conveying such fluid away from the turbine at an intermediate portion of the length thereof. 95

3. A turbine comprising a stator, a hollow compound rotor consisting of a disk wheel and drums, means for introducing the operating fluid to the operative surface of the rotor at one end thereof, means for conveying 100 the whole of such fluid away from such operative surface at an intermediate portion of the length of the rotor and means for reintroducing it to the operative surface at the other end thereof, comprising the hollow 105 body of the rotor, and means for conveying such fluid away from the turbine at the intermediate portion of the length thereof.

In testimony whereof I have signed my name to this specification in the presence of 110 two subscribing witnesses.

ALEXANDER JUDE.
